UNITED STATES PATENT OFFICE.

STONE R. ENBERG, OF WORCESTER, MASSACHUSETTS, ASSIGNOR TO WALDEN-WORCESTER, INCORPORATED, OF WORCESTER, MASSACHUSETTS, A CORPORATION OF MASSACHUSETTS.

RATCHET WRENCH.

Application filed July 2, 1925. Serial No. 41,037.

This application relates to an improvement in ratchet wrenches in which the member to be turned may be operated by oscillation of the handle of the wrench.

5 It is an object of the invention to provide a wrench of this type which will consist of few parts, easy to manufacture, and which at the same time will be rugged and reliable in service.

10 Another object of the invention is to provide a wrench of the type described, in which the turning member may be operated by oscillation of the handle through a very limited space, adapting the wrench to work 15 in limited confines, without any loss of efficiency in operation.

Another object of the invention is to provide a wrench in which each forward pull on the handle causes tighter engagement between the handle and the turning portion, but in which rearward movement of the handle readily disengages the handle from the turning portion.

Various other objects and advantages of 25 the invention will appear as the description thereof proceeds.

Referring now to the drawings, which illustrate a preferred form of the embodiment of the invention:

30 Fig. 1 is a plan view of my improved wrench;

Fig. 2 is a plan view of a modified form of wrench, with one of the side plates removed, showing the rearward position of 35 the handle in dotted lines;

Fig. 3 is a sectional view on the line 3—3 of Fig. 2; and

Fig. 4 is a side view of the nurled head or 40 turning member.

The wrench of my invention comprises a handle portion 1 and turning portion or head 2 which is provided in the center thereof with a suitably shaped opening 3 for receiving the nuts or wrench sockets to be turned by the wrench. The head or collet 2 comprises the cylindrical barrel 4 in which the polygonal opening 3 is located, and includes an integral rim or projection 5 at the center of the barrel, the outer edge of 45 which is nurled at 6 to provide for co-operation of the head member with the handle. The handle comprises a shank portion 1, which is cut away at the end nearest the head to provide a projection or pawl 7, the

forward edge of which is nurled or milled 55 at 8 to correspond with the nurling 6 on the rim 5. The handle and head of the wrench are each pivoted between two plates 9 and 10 which have openings 11 therein to receive the ends of the barrel 4 which project beyond the rim 5 and have openings to receive the rivet 12 on which the handle 1 is pivoted and the rivet 13, which provides additional securing means between the two plates 9 and 10 and acts as a stop to prevent rearward movement of the handle 1 relative to the plates 9 and 10 beyond a predetermined point.

Excluding the rivets, the wrench comprises only four parts,—the handle 1, the head 2, and the plates 9 and 10. The rim 5 is nurled or milled at 6 to provide a plurality of closely spaced projections or teeth 6' running parallel to the axis of the barrel 4, to which the nurling 8 on the pawl 7 of the handle corresponds in size and shape. In the model of the wrench from which the present drawings were made, there were approximately 120 teeth or nurled edges 6' on the rim 5, so that in the operation of 70 the wrench it is only necessary to move the handle rearwardly by about 3 degrees in order to change the grip and permit forward rotation of the head 2. This, as contrasted with the ordinary type of ratchet wrench in 75 which rotation of the handle through 15 to 20 degrees or more is required to move from one tooth of the ratchet to the other, enables the present wrench to operate in a much 80 more confined position than the usual ratchet wrench, because of the very slight oscillation of the handle, necessary to permit a change of grip and forward rotation 85 of the head 2. Since the teeth 6' are shallow as compared to the usual ratchet teeth there 90 is little lost motion in disengaging the pawl 7 of the handle from the head. Furthermore, by providing the rim 5 of the head 2 with nurled or milled teeth of small 95 dimensions, it is possible to completely 100 finish the head 2 in an automatic screw machine, without the intervention of hand work, whereas, with the usual type of ratchet teeth, it is necessary to shape the teeth by the use of a milling cutter, which 105 is expensive both from the standpoint of labor, handling, and materials required. By providing the pawl 7 at the end of the

handle with the corresponding nurl, instead of gripping the head 2 at one point as is the case with the customary pawl, the end of the handle grips the head 2 at a plurality of points, depending upon the number of teeth or projections 8 on the end of the handle 7.

The location of the rivet 12 relative to the end of the handle is such that forward pull upon the handle increases the pressure of the pawl 7 against the rim 5 of the head, and decreases any tendency to slip, which might be incurred by the additional strain on the wrench, whereas the radius of movement of the pawl 7 around the rivet 12 when the handle is moved in the reverse direction quickly and easily disengages the teeth 8 from the teeth 6' on the rim, with only a slight movement of the handle.

Upon the rearward movement of the handle the heel 14 thereof soon after the disengagement of the pawl 7 from the rim 5 contacts with the rivet 13 to cause the handle 1 and the plates 9 and 10 to turn rearwardly around the head 2, which is held stationary by its engagement with the nut or socket being turned, so that on the next forward movement of the handle, the pawl 7 grips a new portion of the rim 5, and forward pull on the handle causes forward rotation of the head 2, to turn the nut or wrench socket with which it is engaged.

In the embodiment of the invention shown in Figs. 2 and 3, the opening 3 is not broached all the way through but has been stopped at the point indicated by the lugs 3' forming a ledge or stop at about the middle of the barrel 4. This prevents the head 2 from slipping down over the nut or wrench socket to which it is applied.

In compliance with the patent statutes, I have illustrated and described preferred forms of embodiment of my invention; but it will be understood, however, that certain

changes and modifications may be made 45 therein without departing from the spirit of the invention or the scope of the appended claims.

I claim:

1. A ratchet wrench comprising a collet provided with a polygonal opening, an exterior mid-section having a nurlled periphery, and exterior end sections of reduced diameter, a pair of side plates provided with holes adapted to receive said end sections, 55 said side plates being spaced apart by the nurlled mid-section of said collet, means for securing said side plates in place consisting of a pair of rivets, a handle pivoted between said side plates on one of said rivets, said handle being provided with a plurality of ratchet teeth adapted to engage the nurlled section of said collet.

2. A ratchet wrench comprising a collet provided with a polygonal opening, stop lugs projecting from the periphery of said opening, said collet comprising an exteriorly nurlled mid-section of increased diameter and end sections of reduced diameter forming shoulders at the ends of said mid-section, side plates provided with holes adapted to receive the end sections of the collet, whereby said side plates are spaced apart by said shoulders, a handle comprising a plurality of ratchet teeth and pivoted on a rivet passing thru said side plates in position for the engagement of the nurlled section of said collet by said ratchet teeth, a second rivet passing between said side plates and forming a stop limiting the rotation of 70 the handle with respect to the side plates, said rivets constituting the sole means for securing the handle, collet, and side plates in assembled relation.

In testimony whereof I have affixed my 85 signature to this specification.

STONE R. ENBERG.
